CAMERA

Raymond A. Grosso, Troy, Mich., assignor to Minnesota
Mining and Manufacturing Company, St. Paul, Minn.,
a corporation of Delaware

Filed Feb. 7, 1969, Ser. No. 15,692

Term of patent 14 years

Int. Cl. D16—01
U.S. Cl. D61—1

FIG. 1

FIG. 2

FIG. 3

FIG. 4

FIG. 5

FIGURE 1 is a perspective view showing the top, front, and left side of a camera of my new design;

FIGURE 2 is a perspective view showing the bottom, rear, and right side of a camera of my new design;

FIGURE 3 is a side elevational view of the right side of a camera of my new design;

FIGURE 4 is a perspective view showing the top, front, and left side of a camera of my new design in extended, operating position; and

FIGURE 5 is a perspective view showing the bottom, rear, and right side of a camera of my new design in extended, operating position.

The dominant features of the design reside in the por-

tions of the drawings shown in full lines. Portions of the drawings are diagonally lined to indicate transparency.

I claim:

The ornamental design for a camera, substantially as shown and described.
